(57) **CLAIM**

The ornamental design of a flashlight, as shown and described.

DESCRIPTION

FIG. 1 is a perspective view showing our new flashlight with a handle of the flashlight in a retracted position, wherein the strap shown by broken lines is shown for illustrative purposes only and forms no part of the claimed design;

FIG. 2 is a top view therof;

FIG. 3 is a bottom view thereof;

FIG. 4 is a front view thereof;

FIG. 5 is a back view thereof;

FIG. 6 is a right side view thereof;

FIG. 7 is a left side view thereof;

FIG. 8 is a perspective view of the flashlight with the handle in an exposed position, wherein the strap shown by broken lines is shown for illustrative purposes only and forms no part of the claimed design;

FIG. 9 is a top view thereof;

FIG. 10 is a bottom view thereof;

FIG. 11 is a front view thereof;

FIG. 12 is a back view thereof;

FIG. 13 is a right side thereof; and,

FIG. 14 is a left side thereof.
